Primary Examiner — George D. Kirschbaum

Assistant Examiner — Richard Kearney

(57) **CLAIM**

I claim the ornamental design for a chair, as shown and described.

DESCRIPTION

The patent or application file contains at least one drawing executed in color. Copies of this patent or patent application publication with color drawing(s) will be provided by the Office upon request and payment of the necessary fee.

- 1.1 is a front view of a chair showing the claimed design;
- 1.2 is a rear view thereof;
- 1.3 is a front, top, right side perspective view thereof;
- 1.4 is a rear, top, left side perspective view thereof;
- 1.5 is a right side view thereof;
- 1.6 is a bottom view thereof; and
- 1.7 is a top view thereof.

1 Claim, 7 Drawing Sheets
(7 of 7 Drawing Sheet(s) Filed in Color)
